UNITED STATES PATENT OFFICE.

JOHN C. LOOK, OF TUDOR, CALIFORNIA.

MOP-HEAD.

SPECIFICATION forming part of Letters Patent No. 695,063, dated March 11, 1902.

Application filed July 17, 1901. Serial No. 68,638. (No model.)

To all whom it may concern:

Be it known that I, JOHN C. LOOK, a citizen of the United States, residing at Tudor, county of Sutter, State of California, have invented 5 a new and useful Improvement in Mop-Heads, of which the following is a specification.

The object is to provide a mop-head with simple devices for tightening the clamp on the mop-cloth. This is accomplished by using 10 a snap-lever pivoted to a ring or annular yoke that is movable along the handle and engages a ratchet attached to the handle. The arrangement is such that the entire handle can be made of wood and of the same diameter 15 throughout.

In the drawings, Figure 1 is a perspective view of the mop-head in an open position. Fig. 2 is a side view in the closed position. Fig. 3 is a yoke on the handle, taken on line 20 $\alpha\alpha$ of Fig. 2.

a is the mop-handle; a' , the clamp-head; a^2 , the clamp device; b , the ratchet on the handle; c , the lever, and d the yoke. The ratchet b is attached to the handle in any of the usual 25 ways. The yoke d is applied by slipping it over the end of the handle and has the diameter enlarged in the direction of the ratchet at d^2 to an extent that allows it to pass over the ratchet when it is brought to the right 30 angle of the handle, as shown in dotted lines $y\bar{y}$, Fig. 2, and as seen in Fig. 3. A suitable catch d^2 is provided in the yoke for engaging the ratchet. The lever c is pivoted in the yoke at d^3 , and a clamp a^2 is pivoted to the 35 lever at the lugs $c' c'$. Any kind of a clamp

and clamp-head may be used, as the yoke maintains the clamp in line with the handle. Also the lever c may be of any desirable shape. A plate e may be used on the handle under the yoke to prevent the yoke from 40 chafing the handle. The yoke d should be of sufficient strength not to compress the sides when the draft of the lever comes on the pivot-box d^3 .

The operation is as follows: The lever c is 45 raised, as in Fig. 1. The mop-cloth is then inserted between the clamp and clamp-head, after which the yoke is placed in the tooth of the ratchet required by the size of the mop-cloth and the lever put down, as in Fig. 2. 50 The draft of the clamp then comes on the lever below the pivot d^3 , and the yoke is held in place by the pressure in the pivot-box d^3 , drawing the catch d^2 into the ratchet b .

Having described my invention, what I 55 claim as new, and desire to secure by Letters Patent, is—

In a mop-head, a handle provided with a clamp-head and with a ratchet, an annular yoke surrounding the handle and ratchet and 60 movable therealong and engaging the ratchet, said yoke having a section of sufficient diameter to operate over the ratchet, a lever pivoted to said yoke and a clamp device pivoted to the lever.

JOHN C. LOOK.
